Des. 186,435
Patented Oct. 27, 1959

186,435

TRANSISTOR CLIP

Robert H. Wilson, Anaheim, Calif., assignor to Northrop Corporation, Hawthorne, Calif., a corporation of California

Application February 19, 1957, Serial No. 44,920

Term of patent 14 years

(Cl. D26—1)

Figure 1 is a perspective view of a transistor clip, showing my new design, the broken line showing being for illustrative purposes only;

Figure 2 is a side elevational view;

Figure 3 is an end elevational view;

Figure 4 is a bottom plan view; and

Figure 5 is a top plan view thereof.

I claim:

The ornamental design for a transistor clip, substantially as shown and described.
